US0D1110944S

(12) **United States Design Patent** (10) **Patent No.:** **US D1,110,944 S**
(45) **Date of Patent:** **** Feb. 3, 2026**

(54) **PORTABLE BATTERY**

(71) Applicant: **ShenZhen YunJi New Energy Technology Co., Ltd**, Shenzhen (CN)

(72) Inventor: **Songlin Xiao**, Shenzhen (CN)

(73) Assignee: **ShenZhen YunJi New Energy Technology Co., Ltd**, Shenzhen (CN)

(**) Term: **15 Years**

(21) Appl. No.: **29/938,860**

(22) Filed: **Apr. 23, 2024**

(30) **Foreign Application Priority Data**

Mar. 29, 2024 (CN) 202430170274.X

(51) **LOC (15) Cl.** **13-02**

(52) **U.S. Cl.**

USPC **D13/103**

(58) **Field of Classification Search**

USPC D13/103, 104, 106, 107, 108, 109, 110,

D13/112, 118, 119, 184, 199

CPC H02J 7/00; H02J 7/0042; H02J 7/0044;

(57) **CLAIM**

The ornamental design for a portable battery, as shown and described.

DESCRIPTION

FIG. 1 is a perspective view of a portable battery showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof; and,

FIG. 8 is bottom plan view thereof.

The broken lines in the drawings depict portions of the portable battery that form no part of the claimed design.

1 Claim, 8 Drawing Sheets
